CAR ROOF

James S. Swann, Chicago, Ill., assignor to P. H. Murphy Company, New Kensington, Pa., a corporation of Pennsylvania

Application September 21, 1936, Serial No. 101,744

13 Claims. (Cl. 108—5.4)

In the well known neutral axis type of roof, there is a series of alternating ribs and channels which span from side to side of the car. This type of roof has important advantages but, in its typical form, it is deep at the ridge and does not conform to the established tunnel clearance outline and, therefore, does not afford maximum headroom and maximum loading capacity. The principal object of the present invention is to overcome these shortcomings of the neutral axis roof. The invention consists principally in shaping the roof sheets to approximate the established tunnel clearance outline crosswise of the car with a substantially flat panel extending lengthwise 10 of the car along the region of the ridge and with the portions between such longitudinal panel and the side plates formed into alternating ribs and channels after the manner of the neutral axis roof, the flat longitudinal ridge panel being 15 reinforced by carline members which operate conjointly with the ribs and channels. It also consists in the parts and arrangements and combinations of parts hereinafter described and claimed.

25 In the accompanying drawings, wherein like numerals refer to like parts wherever they occur,

Fig. 1 is a plan view of a portion of a car roof embodying my invention.

Fig. 2 is an enlarged vertical transverse section through one-half of the roof on the line 30 2—2 in Fig. 1.

Fig. 3 is a similar section on the line 3—3 of Fig. 1.

Fig. 4 is an enlarged section similar to Fig. 2 35 of the eaves portion of the roof.

Fig. 5 is an enlarged fragmentary vertical longitudinal section through the ridge portion of the roof on the line 5—5 of Fig. 1.

Fig. 6 is a similar section through the roof 40 intermediate between the ridge and eaves on the line 6—6 of Fig. 1.

Fig. 7 is a fragmentary perspective view of one of the roof sheets; and

Fig. 8 is a view similar to Fig. 2 illustrating 45 a modified construction.

The present roof comprises sheets A which extend from side plate B to side plate B and have downturned flanges 1 at their ends which are secured by rivets 2 or otherwise flatwise to vertical portions 3 of the side plates. The side plate illustrated in the drawings is W-shaped, with its lower marginal leg 4 disposed vertically against the outer face of the car side 5. The innermost 50 and top most leg 6 extends inwardly with a slight upward inclination and with its inner edge close

to the established tunnel clearance outline X and nearly flush with the inner lining 7 of the car side.

At the middle of each roof sheet is a flat panel 8 which extends transversely of the sheet and longitudinally of the car, this panel being wide enough for a running board. Along each end of the sheet is the narrow marginal flange 1 above mentioned which fits flatwise against a vertical web 3 of the side plate. Between the ridge panel 10 8 and each eaves end of the roof sheet, there are four breaks or changes of direction in the side marginal portions 9 of the roof sheets. The first break 10 represents a very slight downward inclination of the portion of the sheet adjoining 15 the longitudinal ridge panel 8, such portion extending fairly close to the tunnel clearance line. The second break 11 represents a further downward and outward inclination of the sheet substantially parallel with the established tunnel 20 clearance outline to a point fairly close to the break in such established clearance outline. At this point is the third break 12 in the sheet which represents a still further downward inclination preferably with convergence toward the 25 established clearance line to the fourth break 13 in the sheet at the inner margin of the downturned flange 1 thereof. Thus, the main portion of the sheet, namely, the middle longitudinal panel 8 and the side panels 9 thereof, are fairly close to the established tunnel clearance outline. The middle of that portion of the sheet, which lies between the longitudinal middle panel 8 and the downturned flange 1, is depressed to form 30 a channel panel 14 whose width is about one-half the width of the sheet. The above described breaks in the sheet extend through the depressed panels 14 as well as the side panels 9 of the sheets.

The side margins of the roof sheets have upstanding flanges 15 which extend from the sides of the longitudinal ridge panels 8 thereof to or almost to the downturned end flanges 1 thereof, these side flanges being deepest near the middle of their length and tapering, preferably to the vanishing point, at their ends. The sheets are secured together and to intermediate carline members 16, preferably by welds 17. In the construction illustrated in Fig. 5, the carline member is made in the form of a channel with a wide horizontal flange 18 extending outwardly 40 along the top of one side of the channel and with the wall of the other side 19 extended vertically to a higher level than said flange. This upstanding side wall of the carline member is disposed 45 between the upstanding flanges 15 of adjacent 50 sheets.

roof sheets with its top edge substantially flush with their edges and all are welded together with the single line of weld 17 along said edges. The horizontal flange is secured to the underface of the roof sheet by a weld 20 in the angle between its end and the body of the sheet. The edges of the ridge panels of adjacent sheets are preferably not flanged but are spaced somewhat apart and the top edge of the free side of the carline member lies below the margins of adjacent sheets and spans the gap between their edges, and the sheets and carline members are all welded together by the single weld 17 which fills said gap.

In the construction illustrated in Fig. 1, the carline members extend from side plate to side plate and have their ends resting on and welded to the inturned legs of the side plate, and the running board 21 is made by merely painting and sanding the longitudinal ridge panel 8. In the construction illustrated in Fig. 8 however, the carline members 16a terminate considerably short of the side plates and are welded directly to the roof sheets; and the running board comprises a metal sheet 21a welded to in direct surface contact with the longitudinal ridge panel of the roof with its side margins extending beyond the inner ends of the channel panels 14 so as to furnish grips for the trainmen.

The present roof has several advantages. Its flat longitudinal ridge panel is well adapted to support a running board without substantially increasing the thickness of the roof and it is adapted to be used as a running board by applying paint thereto and then applying grit or the like to the wet paint. In either case, it enables the ridge portion of the roof to be located close to the established tunnel clearance outline and it also enables the portions of the roof between said longitudinal ridge panel and the eaves to be located close to said clearance line. At the same time, the termination of the depressed panels, at points outwardly from the longitudinal ridge panel, is made feasible by the use of the carline members with substantial decrease in the overall thickness or depth of the roof, particularly along the region of the ridge and thereby increases the headroom and loading capacity of the car. For this purpose, it is not necessary that the carline member shall extend to and rest upon the side plates, as the formation of the roof sheets into alternating ribs and channels enables them to take care of whatever load the carline members may pass to them. It is also noted that the invention allows considerable variation in the design of the carline members to adapt them to their location and to the stresses to which they will be subject and which they will pass along either to the side plates or to the roof sheets.

It is noted that the work of welding the carline member to the body portion of the sheet may be done at the factory and the sheet with the carline member welded thereto may be shipped as a preassembled unit. Such unit construction is not only economical, but facilitates the work of assembling the roof units into the complete roof.

What I claim is:

1. A car roof comprising side plates, roof sheets extending from side plate to side plate and having their ridge portions substantially flat for a width substantially equal to the horizontal top portion of the established tunnel clearance outline, said sheets having, at their side margins,

upstanding flanges that extend from the sides of the flat ridge portion to near the eaves, carline members located mostly below the sheets but having an upstanding portion between adjacent sheet flanges and with their tops substantially following said clearance outline and flush with the tops of said flanges, and welds along said outline uniting adjacent sheets together and to the intervening carline members.

2. A car roof comprising side plates, roof sheets extending from side plate to side plate and having their ridge portions substantially flat and the portion between said ridge portion and each eaves broken conformably to the established tunnel clearance outline, said sheets having, at their side margins, upstanding flanges that extend from the sides of the flat ridge portion to near the eaves, carline members below gaps between adjacent sheets along said ridge portions and having an upstanding portion between adjacent sheet flanges with its top substantially flush with the tops of said flanges, welds filling said gaps and opposite said edges and uniting adjacent sheets together and to the intervening carline members.

3. A car roof comprising side plates, roof sheets extending from side plate to side plate, carline members located mainly below the roof sheets with portions extending upwardly between the edges of adjacent sheets, and welds close to the established tunnel clearance outline uniting adjacent sheets together and to the adjacent carline member, the ridge portion of the sheets for a width substantially equal to the horizontal top portion of the established tunnel clearance outline being substantially flat and close to said outline and the portion between said ridge portion and each eaves having breaks to conform such portion approximately to the established tunnel clearance outline and having a depressed panel extending along the middle thereof crosswise of the car.

4. A car roof comprising side plates, roof sheets extending from side plate to side plate, carline members located mainly below the roof sheets with portions extending upwardly between the edges of adjacent sheets, and welds close to the established tunnel clearance outline uniting adjacent sheets together and to the adjacent carline member, the ridge portion of the sheets for a width substantially equal to the horizontal top portion of the established tunnel clearance outline being substantially flat and close to said outline and the portion between said ridge portion and each eaves having breaks to conform such portion approximately to the established tunnel clearance outline and having a depressed panel extending crosswise of the car along the middle of said portion, said carline members being longer than the width of said flat ridge portion but terminating short of the side plates.

5. A car roof comprising side plates, roof sheets extending from side plate to side plate and having their ridge portions substantially flat and the portion between said ridge portion and each eaves broken conformably to the established tunnel clearance outline, said sheets having, at their side margins, upstanding flanges that extend from the sides of the flat ridge portion to near the eaves, channeled carline members below gaps between the adjacent sheets along said ridge portions and having an upstanding side portion between adjacent sheet flanges with its top substantially flush with the tops of said flanges, welds filling said gaps and opposite said edges

and uniting adjacent sheets together and to the intervening carline members, and additional welds uniting the other side portions of said carline members to the body portions of the sheets.

5 6. A car roof sheet comprising a ridge portion which is substantially flat for a width substantially equal to the horizontal top portion of the established tunnel clearance outline and the remaining portions having transverse breaks which conform them to the established tunnel clearance outline for car roofs, said sheet having depressed panels extending lengthwise of the sheet along the middle thereof between the flat ridge portion and the respective eaves portions.

10 7. A car roof sheet comprising a ridge portion which is substantially flat for a width substantially equal to the horizontal top portion of the established tunnel clearance outline and the remaining portions having transverse breaks which conform them substantially to the established tunnel clearance outline for car roofs, said sheet having depressed panels extending lengthwise of the sheet along the middle thereof between the flat ridge portion and the respective eaves portions, said sheet having a carline member welded to the underside of its body portion thereof with the side of the carline member projecting laterally beyond the side edge of the sheet.

15 8. A car roof sheet comprising a ridge portion which is substantially flat and the remaining portions having transverse breaks which conform them to the established tunnel clearance outline for car roofs, said sheet having depressed panels extending lengthwise of the sheet along the middle thereof between the flat ridge portion and eaves portions, said sheet having a channel-shaped carline member with one side welded to the body portion of the sheet and with the other side of the carline member extending upwardly and projecting laterally beyond the side edge of the sheet.

20 9. A car roof sheet comprising a ridge portion which is substantially flat and the remaining portions having transverse breaks which conform them to the established tunnel clearance outline, and flanges along their side margins, said sheet having depressed panels extending lengthwise of the sheet along the middle thereof between the flat ridge portion and eaves portions, said sheet having a channel-shaped carline member with one side welded to the body

portion of the sheet and with the other side of the carline member extending laterally beyond the side edge of the sheet and substantially in contact flatwise with said flanges.

25 10. A car roof sheet comprising a ridge portion which is substantially flat, portions which slope downwardly on opposite sides of said ridge portion and terminate in downturned vertical flanges, and upstanding side marginal flanges that extend along said sloping portions only, said side flanges increasing in height for some distance inwardly from said downturned flanges so that the tops of the side flanges substantially follow the slope of the established tunnel clearance outline.

15 11. A car roof comprising side plates, roof sheets extending from side plate to side plate and having a substantially flat ridge portion of a width substantially equal to the top horizontal portion of the established tunnel clearance outline, and depressed panels extending longitudinally of the sheet on each side of said ridge portion, carline members having upstanding side margins which are located between adjacent sheets and follow said clearance outline and welds uniting said carlines and sheets together along said clearance outline.

20 12. A car roof sheet comprising a ridge portion which is substantially flat and of a width approximating the width of the horizontal top portion of the established tunnel clearance outline and portions sloping downwardly on opposite sides of said ridge portion, said sloping portions having depressed panels beginning close to the flat ridge portion and extending close to the respective eaves portions with the undepressed parts of said sloping portions substantially following the established clearance outline.

25 13. A car roof sheet comprising a ridge portion which is substantially flat and of a width approximating the width of the horizontal top portion of the established tunnel clearance outline, portions which slope downwardly on opposite sides of said flat ridge portion, and have depressed panels formed therein and extending from the flat ridge portion to the respective eaves portions, and upstanding side marginal flanges that extend along said sloping portions only with the undepressed parts of said sloping portions substantially following the established clearance outline.

30 40 45 50 JAMES S. SWANN.
